BOLT ACTION PUMP GUN

William B. Goff, Tucson, Ariz.

Application July 15, 1941, Serial No. 402,523

2 Claims. (Cl. 42—16)

This invention relates to a bolt action pump gun, the general object of the invention being to provide means whereby the bolt of a bolt action gun can be manipulated by a slide member which operates similar to a pump gun so that the great strength of a bolt action is secured and at the same time the rapidity of operation of a bolt action gun is increased.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevational view of a gun constructed in accordance with this invention.

Figure 2 is a fragmentary elevational view but showing the bolt in retracted position.

Figure 3 is a view of the front end of the bolt of the gun showing the cartridge extractor carried by a sleeve rotatably arranged on the bolt.

Figure 4 is a section on the line 4—4 of Figure 3.

Figure 5 is a front end view of Figure 3.

Figure 6 is a view of the slotted plate attached to one side of the gun.

Figure 7 is a view of the yoke which is pivoted to the bolt lever.

Figure 8 is an edge view of the yoke.

Figure 9 is a rear view thereof.

Figure 10 is a view of the pin used for pivoting the yoke to the lever.

Figure 11 is a front view of the rear end of the slide member.

Figure 12 is a rear view of said end of the slide lever.

Figure 13 is a view in transverse section taken on the line 13—13 of Figure 2, and drawn to an enlarged scale.

In these views the gun is shown at A and its sliding bolt is shown at B, the lever of the bolt being shown at a, the front end of the firing pin is shown at b and oppositely arranged lugs 1 and 2 are connected to the front of the bolt for sliding in grooves 1', 2' in the bolt chamber of the gun. A collar 3 rotatably fits in a groove in the bolt adjacent the front end thereof and the extractor lever 4 is pivoted to an ear 5 on the collar as shown at 6, a spring 7 engages the rear end of the lever for holding it in position

engaging the rear end of the cartridge. The lug 1 normally fits in a recess in the lever 4. A lug 8 extends from the collar and is arranged opposite the ear 5 and this lug as well as the lug 2 have slots 9, 9' therein so that if the cartridge should stick a knock out pin can be passed through these slots to strike the cartridge to dislodge the cartridge sidewise from the extractor when the bolt is open. As will be understood 10 portions of the grooves 1', 2' in the bolt chamber into which the lugs 1, 2, 8 and the lever 4 move when the bolt is being moved to operated position, have right angular extensions 1'', 2'' for receiving the lugs 1 and 2 so that these lugs will 15 turn into these right angular extensions when the bolt is turned by the lever. However, the lug 8 remains in the straight part of its groove so that the sleeve is prevented from turning and thus the extractor lever remains in its groove 20 during turning movement of the bolt.

A plate 10 is fastened to the right hand side of the breech of the gun and the top part of the plate has an elongated notch 11 therein for clearing the top part of the breech to permit 25 the ejection and insertion of a cartridge and this plate is provided with an elongated slot 12 and a slot 13 has a longitudinally extending part and a wide downwardly extending part 13'. A yoke member 14 has bearings 15 in the upper 30 ends of its prongs for receiving a pin 16 which passes through an arcuate slot 17 in the free end of the bolt lever a. A spring-pressed dog 18 in the pin acts to hold the pin in place but by depressing this dog the pin can be moved to release the yoke from the lever. By having the pin pass through an arcuate slot 17 of the lever binding between said lever and yoke is prevented 35 during a straight up and down motion of the yoke.

40 A block-like lug 19 is formed on the inner face of the yoke adjacent the lower end thereof and this lug slides in the longitudinal part of the slot 13 and moves downwardly into the vertical part 13' when the parts are being manipulated to close the bolt. A projection 20 of circular shape in cross section is connected to the front of the yoke. A slide bar 21 has an offset rear end 22 which forms an inner shoulder 23 of substantially Z-shape. This offset part has 45 a downwardly and rearwardly extending part 24 connected therewith which is formed with an arcuate slot 25 in which the projection 20 of the yoke fits. In front of the shoulder 23 the inner face of the slide bar 21 is formed with a lug 26 50 which operates in the slot 12 of the plate 10.

The front end of the bar 21 is connected to a slide member 28 slidably supported on the underside of the gun barrel.

Thus it will be seen that when the bar 21 is moved rearwardly the slot 25 therein acting on the pin or projection 20 of the yoke will first move the yoke upwardly so that the lever *a* of the bolt will turn the bolt and during this movement the lug 19 will move upwardly in the part 13' of the slot until the lug comes opposite the straight part 13. When this occurs the pin 20 is in the top part of the slot 25 so that further movement of the bar 21 causes the yoke to move rearwardly with the lugs 19 and 26 moving through the longitudinal slots 12 and 13 and this, of course, moves the bolt *B* rearwardly so as to open the breech and cause the extractor 4 to extract the fired cartridge. Then upon forward sliding movement of the bar 21 the bolt is moved forwardly until it reaches closed position and then the arcuate slot 25 engaging the pin 20 causes the yoke to move downwardly so as to partly turn the bolt to lock it in position.

The shoulder 23 on the slide bar 21 will abut and lock against one side of the yoke when the gun action is operated and this shoulder exerts pressure on the yoke during the opening movement.

Thus it will be seen that I have provided a pump action for a bolt action of a gun so that the bolt can be easily and quickly moved to open and closed position by simply moving the rod 21 rearwardly and forwardly.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. In a bolt action gun, a bolt having a lever thereon, an arcuate slot in the lever, a yoke having its upper end forked, a pin passing through the prongs and through the arcuate slot in the lever, a part of the gun having a pair of longitudinally extending slots therein, one of which has a depending part, a lug on the inner face of the yoke engaging said one slot and the depending part therein, a slide member having an arcuate camming slot in its rear end, a pin on the outer face of the yoke engaging the slot camming, a lug on the slide member engaging the other slot of said pair and means for reciprocating the slide member.

2. In a bolt action gun, a bolt having a lever, a yoke pivoted to the lever, a plate connected with the breech of the gun and having a pair of longitudinally extending slots therein, one of which is provided with a depending front portion, a lug on the inner face of the yoke engaging said one slot, a pin projecting from the front face of the yoke, a slide member supported on the gun and having an arcuate camming slot in its rear end for receiving the pin, a lug on the slide member engaging the other slot of said pair and means for reciprocating the slide member.

WILLIAM B. GOFF.
